UNITED STATES PATENT OFFICE:

WILLIAM HUGO MATTHIES, OF ANTWERP, BELGIUM, ASSIGNOR TO WESTERN ELECTRIC COMPANY, OF NEW YORK, N. Y., A CORPORATION OF ILLINOIS.

AUTOMATIC EXCHANGE SYSTEM.

996,500.

Specification of Letters Patent. Patented June 27, 1911.

Application filed November 12, 1910. Serial No. 591,970.

To all whom it may concern:

Be it known that I, WILLIAM H. MATTHIES, citizen of the United States, residing at Antwerp, Belgium, have invented a certain new and useful Improvement in Automatic Exchange Systems, of which the following is a full, clear, concise, and exact description.

The invention relates to a system for moving and switching selectors or other variably adjustable circuit controlling devices in automatic telephone exchanges. In such systems it is customary to advance the selectors in an exchange from a sending station, for example a subscriber's station, by alternately opening and closing, as desired, one side of the metallic circuit leading from the subscriber's set to the exchange, thus causing a number of pulsations to go over this side to a switching relay, which in turn effects the advance of a selector in connection with it at this time. The other side of the line which eventually serves to hold all apparatus necessary for maintaining the connection between the subscriber and the exchange while the interruptions take place in the first side of the line, is as a rule used, after a selector has been operated, to switch this particular selector over to a subsequent selector. This is done by intermittently connecting this side of the line to or cutting it off from earth and correspondingly cutting in or off a relay contained in this line which causes the switching of the selector. Over these arrangements the object of the invention is characterized in this that the selectors or other variably adjustable circuit controlling devices are advanced and switched over the same circuit, this being done in such a way that such devices are advanced through changing the resistance of a permanently closed circuit, the switching, however, being effected by opening the circuit. In case the circuit contains but one side of the subscriber's metallic line, the said arrangement renders it possible for the subscriber to release the connection about to be established at any desired time, *i. e.* also during the operation of a selector by simply opening the other side, over which merely the line relay is excited, when restoring the receiver to its hook. On the other hand, if this said circuit contains both sides of the metallic circuit, it is possible to use the

current traversing the circuit permanently closed during the operation of the selectors, 55 also for the purpose of holding the line or calling relay of the subscriber. A further great advantage of the new arrangement is that it does away with almost every disadvantage caused usually when opening and 60 closing with speed the switching circuit and which practically have led to great inconveniences (for instance breaking down of insulations, burning of contacts). This fact is of great importance with respect to the 65 safe operation of the system.

The drawing represents the scheme of two suitable embodiments of the invention, such portions of the complete telephone system, however, which are unnecessary for an understanding of my invention, being omitted, but it will be understood that my invention as disclosed herein may be used in connection with any suitable system as, for example, that shown and described in my co-pending application, Serial No. 590,650, filed 75 November 4, 1910, for telephone exchange system.

In the arrangement according to Figure 1 the circuit for advancing and switching 80 the selectors contains but the one line *a*, whereas in the arrangement according to Fig. 2 it comprises both lines *a* and *b*. In both cases the subscriber's set *T* besides the usual telephone set is further equipped with 85 a device *NS*, called subscriber sender or number switch, which is suitably placed into a by-box. The meaning of all other parts of the figures will result from the following:

The operation of the circuit shown in Fig. 90 1 is as follows: As soon as the subscriber *T*, desirous of a connection with a second subscriber, removes his receiver from the hook, the following current is cut in: Earthed battery *B*¹ over the winding of line relay *LR*, 95 side *b* of the line, switchhook of set *T*, contact springs *f*¹ and *f*² at the subscriber's sender or number switch *NS*, side *a* of the line, winding of a relay *AR*, ground, back to battery. Relay *AR* cuts in over a local circuit 100 a relay *SR* which in turn indirectly causes the motion of the line finder *LS*, which is merely represented by the contact brushes *b*¹, *b*², *b*³ and contacts *c*¹, *c*², *c*³. The line relay *LR*, on the other hand, earths contact *c*³ of the line finder, corresponding to 105

brush b^3 , over its front contact. As soon as the brush of the moved line finder reaches the earthed contact c^3 of subscriber T, the line finder comes to a standstill, so that 5 brushes b^1 and b^2 rest upon contacts c^1 and c^2 . The particular form and construction of the line finder have nothing to do with the nature of the invention and are therefore not represented. Furthermore the figure 10 does not show that the subscriber's line may also be connected even to a larger number of line finders which are all brought into action when relay AR attracts its armature and sit still when brush b^3 of one of these 15 line finders is the first to arrive at the earthed contact c^3 of the subscriber. The line finder LS now being engaged with the line of the calling subscriber, the line a is then connected over resistance w^1 to the selector relay WR and switching relay UR by means of brush b^1 —possibly after some automatic operations which are of no interest here have taken place previously or in the meantime. During these operations subscriber 20 T has adjusted his sender or number switch NS according to the numeral of the desired subscriber, the apparatus at the exchange being in no way influenced by this procedure. The number switch, for instance, 25 consists of a number of contact disks placed side by side (thousands', hundreds', tens' and units' disks) which are separately adjusted to their corresponding digits and are then released one after the other by means of a 30 wound up clock-work. When returning to their normal position they successively close and open a contact ≈ 1000 , ≈ 100 , ≈ 10 and ≈ 1 35 respectively.

Before the release of the adjusted contact 40 disks the contact springs f^1 , f^2 , f^3 , are thrown into another position in which they are held until the last contact disk has reached its normal position and therefore the springs are suitably moved by a part which is 45 moved from its normal position when the clock-work is wound up, but which is returned to its normal when the clock-work has run down. The contact springs f^1 , f^2 , f^3 are so arranged that the earthed contact 50 spring f^3 already engages with the contact spring f^1 when the contact spring f^2 is still in contact with spring f^1 . Consequently the line relay LR is not cut off when throwing the springs, but this relay receives current 55 over springs f^1 and f^3 before springs f^1 and f^2 are disengaged. The relay AR, however, loses the current necessary to excite it when opening spring f^1 and f^2 and is then cut off from line a in a manner not shown here. By 60 the same operation that brought the contact springs f^1 , f^2 , f^3 into their alternate positions the contact spring f^4 has also been brought against its contact, and line a is connected with earth over resistance w^2 , so that a current 65 can flow from battery B^2 over windings

of relays UR and WR, resistance w^1 , brush b^1 of line finder LS, contact c^1 , line a , contact f^4 , resistance w^2 to earth. This current excites only the switching relay UR, whereas the selecting relay WR does not receive the necessary current for its excitement because of the resistance w^2 being cut in. The switching relay UR attracts its armature thus removing an earth connection consisting of its back contact and armature to line 70 2 and relays R 1000 to R 1. If the subscriber now sets the clock-work of his number switch running, at first the contact ≈ 1000 is closed and opened several times in succession according to the adjustment of its 75 contact disk. At every closing of the contact the resistance w^2 is bridged through a shunt to earth, the current flowing over line a thus being intensified. In consequence the selecting relay WR alternately attracts its 80 armature according to the closings of the contact, dropping it again according to the openings of the contact. When being excited, the selecting relay WR always cuts in a current flowing from battery B^3 over the 85 electromagnet of the selector or switch W 1000, righthand armature and back contact of relay R 1000, front contact and armature of relay WR to earth. Corresponding to these circuit closings the selector W 1000 is 90 advanced in a predetermined manner.

When the contact disk belonging to contact ≈ 1000 has returned to its normal position, contact f^4 is opened for a short time before the contact disk of contact ≈ 100 is released. The switching relay UR being constantly excited by the current above described during these switching operations, is now deprived of its current and thus cuts in a current over its armature and back contact, this current 105 exciting relay R 1000 by flowing from battery B^4 over contact f^5 , which is closed when starting selector W 1000, then right-hand winding of relay R 1000, line 2, back contact and armature of relay UR to earth. Relay 110 R 1000 attracts its armatures and shifts the connection over its right-hand front contact from front contact of selecting relay WR to the right-hand armature of relay R 100. On the other hand it closes the circuit of its 115 left-hand holding winding through its left-hand front contact, thus remaining excited even after earth line 2 has been cut off, which occurs when closing contact f^4 before starting the release of contact disk of contact ≈ 100 and at the same time again exciting switching relay UR by current flowing from battery B^2 over resistance w^2 . When returning the disk of contact ≈ 100 to its normal position, the same operations will happen as above described with the difference, however, that now the impulses caused by selecting relay WR will energize the electromagnet of selector W 100, thus advancing 120 this selector. After restoring of contact ≈ 100 125

disk of contact z 100, contact f^4 is again opened for a short interval, thereby energizing relay R 100 by means of relay UR, relay R 100 cutting off selector W 100 from contact of selecting relay WR, connecting the latter to selector W 10 instead. Similar operations recur when restoring contact disks of contacts z 10 and z 1, thereby advancing selectors W 10 and W 1 respectively.

10 If the clock-work of the number switch or a part connected therewith returns to its normal position, contact f^4 is opened definitely. At the same time contact springs f^1 , f^2 , f^3 are restored to their former position, *i. e.* lines a and b are again connected, and this before the earth over contact spring f^3 is removed from line b . Consequently the line relay LR, which meanwhile was bridged to lines a , b in a manner of no account to the 20 nature of the invention (for instance by grounding line a) remains energized as before. Relay LR does not become deenergized before the subscriber restores his receiver to the hook at end of conversation.

25 The switch KD is designed to be operated when before or after the complete operation of system as herein disclosed it is desired to restore the relays R 1000, R 100, R 10 and R 1 to their normal deenergized condition.

30 This switch K may be and is preferably automatically operated by any desired means at the proper stage in the operation of the system but since the means for operating it form no part of the present invention, such 35 means are not shown. All other apparatus used for establishing the connection may be restored to their normal and made ready for a new connection in any desired manner.

The chief difference between circuit shown 40 in Fig. 1 and circuit shown in Fig. 2 is that the circuit for advancing and switching the selectors contains not only line a , but both lines a and b . This arrangement renders it possible to use the permanent current flowing 45 over the circuit during the operation of the various selectors also as a holding current for the line relay of the subscriber. In view of the fact that this permanent current is intermittently cut off when switching the 50 selectors, whereas the line relay must necessarily remain constantly excited, the arrangement shown in Fig. 1 will have to undergo some changes which will be outlined in the following:

55 The operation of the circuit shown in Fig. 2 is as follows: When the receiver is removed from its hook at subscriber's station T, the line relay LR becomes energized by a current which flows from battery B¹ over winding of relay LR, line b , contact springs f^1 and f^2 , switchhook of subscriber T, contact f^4 , line a , winding of relay AR to earth. The relay AR causes the 60 starting of the line finder LS, which comes to a standstill as soon as its brush b^3 arrives at the contact c^3 which is grounded through line relay LR. When winding up the clock-work serving to return the contact disks of number switch NS, the contact springs f^1 and f^2 are opened. Inasmuch, however, as contact spring f^1 makes contact with contact spring f^3 before this, line relay LR remains energized by a current flowing from battery B¹ over line b , contact springs f^1 , f^3 , f^6 , f^7 to earth. Now the contact spring f^4 and simultaneously or shortly after the set of contact springs f^4 , f^7 and f^8 are operated. This set of springs, similar to contact springs f^1 , f^2 and f^3 , is so arranged as to separate springs f^6 and f^7 but after the 70 springs f^6 and f^8 come into contact. Consequently the line relay LR remains energized, although earth has been removed from the subscriber's set, by a current flowing from battery B¹ over winding of line relay LR, 75 line b , contact springs f^1 , f^3 , f^6 , f^8 , resistance w^2 , contact spring f^4 , line a , resistance w^1 , windings of relays WR and UR and earth. This current also energizes switching relay UR, whereas the selecting relay 80 WR does not receive the necessary current for its excitement owing to resistance w^2 being cut in. If now the contact disk of the number switch NS corresponding to contact z 1000 is released and restored, contact z 1000 is alternately closed and opened according to the adjustment of its contact disk. Each time the contact is closed, the resistance w^2 is bridged over, so that the 85 current flowing in the last mentioned circuit is intensified each time and excites the selecting relay WR. After the contact disk corresponding to contact z 1000 has returned to normal but before the contact disk corresponding to contact z 100 has ceased rotating, the contact springs f^6 , f^7 and f^8 and simultaneously or shortly after also contact spring f^4 are intermittently operated, with the result of line relay LR again receiving 90 current over contact springs f^6 , f^7 and earth 95 at subscriber's set, whereas relay UR now loses its current. After all this has taken place, contact springs f^4 and f^6 , f^7 , f^8 are returned to their first mentioned position, and the disk of contact z 100 commences to rotate. The operations now taking place are the same as described above and recur at 100 the rotation of the disks belonging to contacts z 10 and z 1 respectively. If all disks 105 have returned to their normal, all contact springs are also returned to the normal position shown in the figure. The line relay LR, which in the meantime is bridged across lines a and b in a manner not shown here, 110 is now excited over contact springs f^1 , f^2 and becomes deenergized only when the receiver 115 is returned to its hook at end of conversation. In all other respects the selecting devices of Fig. 2 are the same as in Fig. 1 and are therefore not shown here. 120

Both modifications show that the circuit containing the relays WR and UR besides the resistance w^2 at the subscriber's set also contains at the exchange a resistance w^1 which is cut in permanently in the line. This resistance serves the purpose of rendering the intensity of the current flowing through the circuit as independent as possible from the length of line a and lines a , b respectively, that is to say independent from the resistance increasing together with the distance between subscriber's set and exchange, thus making it feasible that but one adjustment of the selecting relay WR is necessary for all subscribers' lines connected to the exchange in question. With this respect an advantageous effect might also be produced by suitably proportionating the resistance w^2 . Naturally the invention is not restricted to the modifications shown. For instance in the place of subscriber's set T there might be an operator's position of the exchange containing the selecting arrangement or of another exchange, without offending against the nature of the invention.

I claim:

1. In a telephone exchange system, the combination with variably adjustable circuit controlling devices, of a common controlling circuit therefor, a resistance in said circuit, and means whereby said devices are adjusted in response to resistance changes in said circuit and are switched by the opening 35 of said circuit.

2. In a telephone exchange system the combination with variably adjustable circuit controlling devices, of a common circuit for controlling such devices, a resistance in said 40 circuit, a shunt adapted to be closed around said resistance, and two relays also in said circuit, one of which is operated each time said shunt is closed to adjust the device associated with the circuit and the other relay 45 deenergized upon the opening of the circuit to switch the circuit from one device to the next device.

3. In a telephone exchange system, the combination with variably adjustable circuit 50 controlling devices, of a common controlling circuit therefor, a resistance in said circuit, a shunt adapted to be closed around said resistance, two relays in said circuit one operated upon the shunting of the resistance 55 to adjust the associated device and the other deenergized upon the opening of the circuit to switch the circuit from the first associated device to the next electromechanism, a line relay associated with said circuit, and a 60 source of current supplying said relays in said circuit and said line relay.

4. In a telephone exchange system the combination with variably adjustable circuit 65 controlling devices, of a common controlling circuit therefor extending from a subscriber's

station to an exchange, a resistance in said circuit, a shunt adapted to be closed around said resistance, a line relay associated with said circuit, a pair of controlling relays in said circuit, one of said relays being operated by the closure of said shunt and the other of said relays being deenergized by the opening of said circuit, said pair of relays being adapted to control said devices, a source of current supplying said line relay 75 and said controlling relays, and an equalizing resistance in said circuit at the exchange.

5. In a telephone exchange system the combination with a plurality of variably adjustable circuit controlling devices, of a common controlling circuit therefor, a resistance in said circuit, electromagnetic means in said circuit operating in response to resistance changes therein to adjust said devices, a relay controlled over said circuit and associated with one of said devices for shifting the control from said device to another of said devices, and means operated in the adjustment of the first said device to render 90 said relay operative.

6. In a telephone exchange system the combination with a plurality of variably adjustable circuit controlling devices, of a common controlling circuit therefor, a resistance in said circuit, electromagnetic means in said circuit operating in response to resistance changes therein to adjust said devices, a relay associated with one of said devices operating in response to the opening of said circuit for shifting the control from such device to another of said devices, and means operated in the adjustment of the first said device to render 100 said relay operative.

7. In a telephone exchange system, the combination with a telephone circuit, of a plurality of variably adjustable circuit controlling devices adapted to be brought one after another into association with said circuit, relays controlling said devices, said relays being responsive to resistance changes in said circuit to adjust said devices and responsive to the opening of the circuit to shift said circuit from association with one 110 of said devices to another of said devices.

8. In a telephone exchange system, the combination with a telephone circuit, of a plurality of variably adjustable circuit controlling devices, and relays common to said devices controlling the adjustment of said devices in response to resistance changes in said circuit and controlling the association of said devices one after another with said circuit in response to the opening of said 120 circuit.

9. In a telephone exchange system, the combination with variably adjustable circuit controlling devices, of a circuit for controlling such devices and two relays also in 130

said circuit, one of which is operated by resistance changes in said circuit to adjust the devices one after another as they are associated with the circuit, and the other relay 5 operated upon the opening of the circuit to switch the circuit from one device to the next device.

In witness whereof I hereunto subscribe my name this 4th day of November A. D., 1910.

WILLIAM HUGO MATTHIES.
